UNITED STATES PATENT OFFICE.

CHARLES E. HAWKINS, OF BRADDOCK, PENNSYLVANIA, ASSIGNOR OF ONE-HALF TO ALFRED T. THOMPSON, OF BRADDOCK, PENNSYLVANIA.

WRENCH.

No. 885,003.

Specification of Letters Patent. Patented April 14, 1908.

Application filed May 17, 1907. Serial No. 374,232.

To all whom it may concern:

Be it known that I, CHARLES E. HAWKINS, a citizen of the United States of America, residing at Braddock, in the county of Allegheny and State of Pennsylvania, have invented certain new and useful Improvements in Wrenches, of which the following is a specification, reference being had therein to the accompanying drawing.

10 This invention relates to improvements in wrenches of that type commonly styled "monkey" wrenches.

The invention has for its object to provide a strong and durable wrench that can be 15 easily and quickly adjusted.

Another object of this invention is to provide a simple and inexpensive wrench wherein novel means is employed for quickly adjusting the movable jaw of the wrench or minutely adjusting the same, whereby the movable jaw can be quickly placed in engagement with an object and then further adjusted to take a positive grip upon the object.

With the above and other objects in view, 25 which will more readily appear as the invention is better understood, the same consists in the novel construction, combination and arrangement of parts to be hereinafter more fully described and then specifically pointed 30 out in the appended claims.

Referring to the drawing forming part of this specification, like numerals of reference designate corresponding parts throughout the several views, in which:

35 Figure 1 is an elevation of a wrench constructed in accordance with my invention, Fig. 2 is a vertical sectional view of a portion of the wrench partly in elevation, Fig. 3 is a horizontal sectional view of a wrench, Fig. 4 is an elevation of a worm used in connection 40 with the wrench.

To put my invention into practice, I construct my improved wrench of a shank 1 having a toothed edge 2. The shank carries a 45 fixed jaw 3 and a conventional form of handle 4.

Upon the shank 1 is located a movable jaw 5 having straps 6 and 7 surrounding the shank. The jaw 5, at its lower end adjacent 50 to the strap 7 is provided with a recess 8, for a revolvable worm 9, said worm meshing with the toothed edge 2 of the shank 1. The worm is retained within the recess 8 by a vertically disposed pin 10 held within the jaw 5 55 by a screw 11.

The strap 7 is larger than the strap 6 providing clearance 12 for the shank 1. In the clearance of the strap 7 is fixed a spring or resilient strip of metal 14, which is secured to the strip by rivets 15. The spring 14 is 60 provided with a curved end 16 bearing against the rear or plain edge of the shank 1, said spring normally holding the toothed edge 2 of the shank 1 in engagement with the worm 9 of the movable jaw. The inner 65 sides of the strap 6 are beveled, as at 17, while the jaw 5 is beveled at 18 said jaw and strap being beveled to permit of a wabbling or rocking movement of the movable jaw 5 upon the shank 1, when being adjusted.

To quickly adjust the movable jaw 5 it is only necessary to press inwardly upon the strap 7 to disengage the worm 9 from the toothed edge 2 of the shank 1, and then the jaw 5 can be moved to any desired position 70 upon the shank of the wrench. When the strap 7 is released, the spring 14 immediately moves the jaw 5 whereby the worm 9 will engage the toothed edge 2 of the shank 1 and hold the movable jaw 5 in a fixed position with relation to said shank.

To minutely adjust the jaw 5, it is only necessary to rotate the worm 9, and the jaw 5 will be slowly fed in either direction upon the shank 1.

My invention particularly resides in the simplicity of construction, and the positive means which I have employed for quickly and minutely adjusting the movable jaw of the wrench.

The wrench is constructed of strong and durable metal, capable of withstanding rough usage to which it is subjected.

What I claim and desire to secure by Letters Patent, is:—

A wrench comprising a shank having a toothed portion and fixed jaw carried by one end of the shank, a handle fixed to the opposite end of the shank, a movable jaw slidably-mounted upon said shank, said movable jaw at its upper end formed with a laterally-extending strap surrounding and projecting from the shank, said strap having its inner end beveled, said movable jaw provided at its lower end with a recess in the 105 forward face thereof, and further having a laterally-extending strap adapted to surround said shank, said lower strap of greater length than said upper strap and so that the inner face of the lower strap will extend in a 110

plane in which extends the outer face of the upper strap, a spring having its lower end fixed rigidly to the inner face of the lower strap, said spring having its lower edge flush with the lower edge of the lower strap and said spring having its upper end bowed and the remaining portion straight, said spring of a length as to terminate at a point removed from the upper strap, a vertically-extending pin detachably carried by said movable jaw and extending across the re-

cess, a worm journaled upon said pin engaging the toothed edge of the shank, and means extending in the lower portion of the movable jaw and through said pin for detachably connecting it in position. 15

In testimony whereof I affix my signature in the presence of two witnesses.

CHARLES E. HAWKINS.
